UNITED STATES PATENT OFFICE.

HARRY BRATTEN BRANDON, OF WORCESTER, MASSACHUSETTS, ASSIGNOR OF ONE-HALF TO JOHN E. SCHRODER, OF WORCESTER, MASSACHUSETTS.

BRUSH-CLEANING DEVICE.

Application filed October 12, 1920. Serial No. 416,489.

To all whom it may concern:

Be it known that I, HARRY BRATTEN BRANDON, a citizen of the United States of America, residing at the city of Worcester, 5 in the county of Worcester and State of Massachusetts, have invented new and useful Improvements in Brush-Cleaning Devices, of which the following is a specification.

This invention relates to a machine for cleaning hand brushes. While capable of general use for that purpose, it is particularly adapted for cleaning commercial paint brushes which have 10 been filled with paint and become hardened by failure to clean when the paint was fresh. On January 13, 1900 I patented in Sweden under #11,830, a device for cleaning artists' brushes. These brushes are 15 very small and soft, being made of camel's hair generally. The principle of that machine involves the revolution of a complete cylindrical brush having radial bristles in contact with the artist's brush. Its usefulness, 20 was very limited on account of the fact that the bristles of the machine brush were constantly impinging on the bristles of the brush being cleaned. This resulted in bending the camel's hair bristles back 25 when the machine was started and keeping them in that position as long as the machine operated. Therefore, the machine was ineffective, even for cleaning camel's hair brushes of a very small size, and was absolutely inoperative for cleaning anything 30 like a heavy journeyman's paint brush through which paint had permeated and on which it had hardened.

I have now discovered what I believe to 35 be the true principle of cleaning such brushes. This principle is, of course, adapted for the cleaning of smaller brushes and in fact brushes used for other purposes than painting, but its principal utility is for the 40 cleaning of commercial paint brushes.

Instead of providing a rotating cylindrical cleaning brush having a continuous body of bristles all the way around it, and consequently acting always in the same 45 manner on the bristles of the brush to be cleaned, I engage the latter rapidly with a plurality of separated tufts of stiff bristles one after the other. In this way the paint brush is given a quick blow by a tuft 50 of comparatively stiff bristles and then re-

leased. After the bristles of the paint brush have sprung back to their straight position they are again struck quickly by the same or another tuft of bristles. Furthermore, the tufts that are used in the above mentioned manner carry a liquid cleaning compound, of any desired or suitable character, into contact with the brush to be cleaned. I provide in addition paddles which also throw the cleaning liquid on the 60 brush to be cleaned. The invention involves 65 these features and others as will appear.

Reference is to be had to the accompanying drawings in which—

Fig. 1 is an end elevation of a brush 70 cleaning machine embodying one form of my invention;

Fig. 2 is a perspective view of an adjustable brush holder which I can use with 75 the invention;

Fig. 3 is a side elevation of the machine;

Fig. 4 is a side elevation of one form of 80 cleaning element in the machine;

Fig. 5 is a plan of one form of holder for the cleaning element;

Fig. 6 is a transverse sectional view of 85 the machine illustrating the action thereof;

Fig. 7 is a longitudinal sectional view of the machine;

Fig. 8 is a similar view showing certain 90 modifications constituting the preferred form, and

Fig. 9 is a plan of the shaft shown in 95 Fig. 8 illustrating a preferred means for holding the cleaning element.

I have shown the machine as mounted on a suitable baseboard 1 on which are secured supports 2 and 3 for carrying a rigid cylinder 5. This cylinder is held in stationary position and is shown as closed at one end by a tight fitting cap 6. At the opposite end it is shown as having a cap 7 hingedly mounted at its lower edge, as at 8, on the cylinder. This is held in locked position against the cylinder by means of a spring 9 having a curved bearing terminal 10 frictionally engaging a projection on the end of the cylinder. At both ends the cylinder is shown as having its caps connected to it by a rabbeted edge 11 to seal the joint. 105 In this way the ends can be removed, although stationary permanent ends can be employed if desired.

A longitudinal shaft extends through the two caps or ends of the casing. In the form 110

shown in Figs. 4 and 5 this shaft is formed of two parts 12^a and 12^b and provided with offset portions 13 and 14 opposite each other to provide a space 20, of rectangular or 5 other desired form, for holding a bunch or tuft of bristles 19. In other words, this constitutes a brush cleaning element. In this form I have shown the parts 12^a and 12^b together as constituting a cylinder, each 10 one being semi-cylindrical in form. They are held together by providing their ends with screw threads 16 on which nuts 18 are provided. In this way they are caused 15 to clamp the bristles 19 in position. These bristles preferably are formed of wire so that they will be stiffer than the bristles of the brush being cleaned. Two opposite tufts are formed by clamping the wires at the center as shown.

20 It is intended to provide a brush cleaning composition in liquid form in this cylinder and to fill it deeply enough so that the brush cleaning element 19 will go deep down into it. The shaft 12 is rotated by any suitable 25 means, as for example, a gear 31 on one end of the shaft meshing with a larger gear 29 having a crank handle 30 thereon. This gear 29 is shown as mounted on a shaft 28 supported by a bracket 27. The shaft 12 is held 30 at this end by a collar 27 and at the other end by a collar 34 and a nut 35 outside.

The form of device for holding the cleaning 35 element just described is suitable for use on this machine, but I prefer to use a slotted shaft 12 as shown in Figs. 8 and 9. Diametrically through this shaft extend a plurality of longitudinal slots 32. The central slot is the equivalent of the space 20 above referred to. It is designed to hold the 40 tuft of bristles which projects in both directions from the shaft, both ends of which are depended upon for cleaning purposes. The bristles are held in place by set screws 33. In the other two slots 32 I place vanes 45 30 and secure them by screws 33 with which these slots are provided. I have shown the brush cleaning element 19 as mounted at the middle of this shaft and the two vanes as mounted on opposite sides of it. They are 50 provided to throw the liquid from the bottom of the receptacle toward the brush to be cleaned.

The cylinder 5 is provided with an opening 36 through its wall for receiving a paint 55 brush or other brush 36 to be cleaned. If desired I can operate the machine with the parts above described but I have shown a device for locating the paint brush in the form of a collar 21. This is adjustably 60 mounted to fit the external surface of the cylinder 5 and is provided with a knob 23 by which it can be turned circumferentially thereon. This collar is provided with a series of openings 24 and 25, the former being 65 shown as rectangular and the latter of an-

other shape. These forms of openings are provided for the purpose of conveniently receiving brushes of different sizes and shapes. In order to hold this collar against displacement longitudinally I have provided the cylinder with pins 22. An opening in the cylinder is made wide and long enough to receive the largest paint or other brush that has to be cleaned. As the collar 70 21 covers up this opening I have provided a mark M on the cylinder in line with it so as to assist the operator in lining up the small opening 24 or 25 with the large brush opening in the cylinder.

In operation, when it is desired to clean a brush, the cylinder is provided approximately one third full with turpentine or gasoline or other solution having a solvent effect on paint or other material to be removed from the brush. If the collar 21 is 80 used, it is turned until the selected opening 24 or 25 is in line with the mark M. Then the paint brush 36 is inserted through the two registering openings and positioned as 85 shown in Fig. 6. The operator can hold this brush with one hand somewhat yieldingly and turn the crank 30 with the other. On account of the gearing shown he can 90 rotate the shaft 12 at a high speed. This causes the vanes 30 to pass through the liquid at the bottom of the cylinder and to throw it against the walls of the cylinder and also toward and against the bristles of the paint brush.

Furthermore, the brush cleaning element 19 rotates through the liquid rapidly. This 100 has two functions. It separates the bristles of the brush by its intermittent contact, allowing the bristles to spring back to their normal straight position immediately. It 105 also splashes the paint cleaning liquid against the bristles of the paint brush at a time when the bristles thereof are in the act of being separated. In this way the cleaning liquid will freely enter all spaces between the bristles of the paint brush.

The fact that the bristles or wires 19 are separated from each other, or formed in tufts spaced apart circumferentially, constitutes an important feature of the invention because if a continuous brush were employed having a continuous operating surface, as shown in my prior Swedish patent, the flexing of the bristles of the paint brush back and forth would not take place. In 120 that case the bristles would be bent and kept substantially in that position, but according to the present invention they are bent quickly out of their normal position and then allowed to spring back by their natural 125 resiliency before they are again engaged by one of the tufts of wire bristles. The action of the cleaning element is intermittent. It is to be noted that it is while they are being bent back that they are saturated with the 130

paint cleaning liquid carried up from the supply below by the wires 19. These wires are close enough together so that they carry a considerable amount of this liquid with them by surface tension. They also can be rotated fast enough to throw it from them by centrifugal force. The action of the vanes 30 is to splash a considerable quantity of paint cleaner around the casing and some 10 of it will fall against the brush being cleaned at all times during the revolution of the shaft.

Although I have illustrated and described more than one form of the invention I am 15 aware of the fact that other modifications can be made therein by any person skilled in the art without departing from the scope of the invention as expressed in the claims. Therefore I do not wish to be limited to all 20 the details of construction herein shown and described but what I do claim is:—

1. In a machine for cleaning brushes, the combination of a shaft, a tuft of wire bristles projecting radially from said shaft 25 with a vacant space around it, means for rotating said shaft, means for locating a brush to be cleaned with its bristles in a position to be engaged by the wire bristles as the shaft is rotated, whereby said wire bristles will 30 tend to bend the bristles of the brush to be cleaned suddenly out of their normal position and will then pass on by them, allowing them to bend back by their own resiliency, and will thereafter strike them again and repeat 35 the process, and means for throwing a

liquid cleaning medium into the brush while the bristles are separated.

2. In a machine for cleaning brushes, the combination of a receptacle adapted to receive a brush cleaning liquid therein, a shaft 40 above the liquid, a tuft of wire bristles projecting radially from said shaft, means for rotating said shaft, means for locating a brush to be cleaned with its bristles in a position to be engaged by the wire bristles 45 as the shaft is rotated, whereby said wire bristles will bend the bristles of the brush and carry the brush cleaning liquid with them into contact with the bristles of the brush while they are bent, and vanes on said 50 shaft also dipping into the liquid and arranged to throw the liquid against the walls of the cylinder and the bristles of the brush.

3. The method of cleaning brushes which consists in suddenly imparting a blow to the 55 bristles thereof by a body of stiff bristles to bend and separate the bristles of the brush to be cleaned, allowing the bristles to spring back to normal position, and at the same time throwing a liquid cleaning compound 60 into the brush while the bristles are separated and bent out of normal position.

In witness whereof he has hereunto set his hand and affixed his seal, this ninth day of October, 1920.

HARRY BRATTEN BRANDON. [L.S.]
